[57] CLAIM

The ornamental design for a power rocker base for an infant seat, as shown and described.

DESCRIPTION

FIG. 1 is a perspective view of a power rocker base for an infant seat showing my new design;

FIG. 2 is a front elevational view;

FIG. 3 is a rear elevational view;

FIG. 4 is a top plan view;

FIG. 5 is a left side elevational view;

FIG. 6 is a right side elevational view; and

FIG. 7 is a bottom plan view thereof.

FIGS. 2 through 7 have been drawn on an enlarged scale with respect to FIG. 1.

FIG. 1

FIG. 2

FIG. 3

FIG. 4

FIG. 5

FIG. 6

—FIG. 7
